TURRET TYPE LAST PULLING AND
RELASTING MACHINE

John T. Lancaster, Newton, Mass., assignor to
United Shoe Machinery Corporation, Flemington, N. J., a corporation of New Jersey

Application October 17, 1947, Serial No. 780,381

17 Claims. (Cl. 12—15)

1

This invention relates to machines for use in the manufacture of shoes and is herein disclosed as embodied in a conveyor type machine having a plurality of operating stations at one of which are provided instrumentalities for both delasting and relasting a shoe. In the manufacture of certain types of shoe the shoe is assembled tightly upon a last from which it must be removed to enable it to be subjected to a stitching operation, and after the shoe has been stitched it must be relasted to prepare it for subsequent operations.

It is an object of the present invention to provide a machine of the conveyor type provided with means for delasting and relasting a shoe at one of its operating stations. In accordance with a feature of the invention the illustrative machine is provided with a last support movable through a plurality of operating stations and with means at one of said stations for loosening a shoe upon a last on the last support. As shown herein, the illustrated machine is also provided with means for relasting the shoe after the stitching operation has been performed. The machine is so arranged as to enable the shoe to be relasted conveniently upon the same last on which it was originally assembled. The delasting and relasting operations may be performed by mechanism comprising a driven friction element the direction of which may be reversed to enable it to perform either operation at will. The illustrated machine is further provided with means for moving the last support from one station to another and for automatically locking it at the several stations.

These and other features of the invention, including certain details of construction and combinations of parts, will now be set forth in connection with an illustrative machine and will be pointed out in the appended claims.

Referring now to the drawings,

Fig. 1 is a side elevation, partly in section, of an illustrative machine embodying the invention;

Fig. 2 is a plan view of the machine shown in Fig. 1;

Fig. 3 is a front elevation of the machine;

Fig. 4 is an enlarged side elevation of a shoe in relation to the relasting mechanism;

Fig. 5 is an enlarged side elevation, partly in section, of a conveyor carriage and mechanism associated therewith;

Fig. 6 is a detail view in radical section of a portion of the mechanism shown in Fig. 5;

Fig. 7 is a plan view of the relasting instrumentalities;

Fig. 8 is a sectional view in front elevation of

the reversing gears for driving the friction belt; and

Fig. 9 is a plan view showing a portion of the conveyor mechanism.

5 The purpose of the illustrated machine is partially to remove a lasted shoe S (Figs. 1 and 2) from its last L, convey the shoe while loose upon the last to within reach of the operator of a Littleway stitching machine (who removes the 10 shoe from its last, presents it to the stitching machine, and replaces it, after stitching, loosely upon the last), convey the stitched shoe back to its original position, and force the shoe more firmly upon the last. The machine thus operates 15 between two stations, one of which, indicated by the reference numeral 20 (Figs. 1 and 2), is the loading and unloading station and the other of which, indicated by the reference numeral 22, is the stitching station.

20 The operations of delasting and relasting are performed at the loading station 20. The delasting and releasting apparatus comprises a driven belt 24 frictionally engageable with the counter portion of the shoe S. A reversing mechanism

25 26 (Fig. 8) is provided to enable the belt 24 to be driven in one direction for delasting and in the opposite direction for relasting. The last L is carried by a jack 28 which is mounted for

30 swinging movement upon a carriage 30 to enable the operator to force the counter portion of the shoe against the friction belt 24. The carriage 30 is guided upon a circular horizontal track 32. It is driven by a constantly rotating ring 34 to which

35 it may be coupled at will and from which it is automatically uncoupled upon arrival at either of the stations 20 or 22. The ring 34 is driven in a counterclockwise direction as seen from above and as indicated by the arrow on Fig. 2. Several

30 carriages similar to the carriage 30, and similarly numbered on the drawings, are provided, and the uncoupling mechanism of each is so arranged

35 that a carriage will automatically be uncoupled from the driving mechanism before striking a carriage preceding it which is held stationary at

40 one of the operating stations. The coupling of the carriage to the driving mechanism is always effected by the operator and the uncoupling of the carriage is always automatic, without the intervention of the operator.

45 The supporting structure of the machine consists of a column 36 (Figs. 1 and 3) adapted to rest upon the floor and supporting a head 38 (see also Fig. 8) having an upwardly extending

cylindrical or sleeve-like portion 40. Rigidly mounted on the upper portion of the sleeve 40 is

2

a four-armed spider 42 which at the radial extremities of its arms carries the track 32. The rotating ring 34 is carried upon the extremities of the arms of a six-armed spider 44 having a hub 46 which is journaled for rotation upon an exterior finished surface of the sleeve 40. The hub 46 rests upon a hardened steel washer 47 which is supported upon a horizontal circular flange 48 integral with the head 38 and which thus carries the vertical thrust resulting from the weight of the ring 34 and its supporting structure. Formed upon the upper portion of the hub 46 are gear teeth 50 which mesh with a pinion 52 secured upon a vertical countershaft 54 journaled in the hub of the stationary spider 42. Also secured upon the shaft 54 is a gear 56 which meshes with a pinion 58 secured upon the upper portion of a vertical shaft 60 which is journaled in the sleeve 40. Rotation of the shaft 60 is effected through gearing 62 (Fig. 3) by a motor 64 mounted on a bracket 66 secured upon the column 36. The ring 34 is thus driven in the same direction as the shaft 60.

The friction belt 24 runs over a pair of rolls 68 (Fig. 1) and 70 (Fig. 8), the roll 68 being an idler roll and the roll 70 being driven. The roll 68, which, except for a groove 69 (Fig. 7) formed in its periphery, is similar in construction to the roll 16 disclosed in United States Letters Patent No. 1,882,083, granted October 11, 1932, upon an application filed in the name of George A. Miner, is mounted on a shaft 72 journaled in bearings carried by a bracket 74 which is mounted upon one of the arms of the stationary spider 42. The groove 69, into which the heel end of the shoe is forced, enables the belt 24 to exert upon the shoe a considerable tractive force which is distributed over a wide area. The roll 70 is mounted upon a shaft 76 which is journaled in suitable bearings 77 carried by a bracket 78 mounted on two of the arms of the spider 42.

The driving and reversing mechanism for the friction belt 24 is best shown in Fig. 8. It comprises a bevel gear 80 mounted upon the upper end portion of the shaft 60 and meshing simultaneously with a pair of coaxial bevel gears 82 and 84 which are thus constantly driven in opposite directions, the direction of rotation of the gear 82 being counterclockwise, as seen in Fig. 1, and the direction of rotation of the gear 84 being clockwise. The gears 82, 84 are freely rotatable upon the shaft 76 and are held against movement away from each other by the engagement of their hubs with the bearings 77. Extending from the inner face of the gear 82 in a direction parallel to the shaft 76 is a clutch pin 86 and extending also parallel to the shaft 76 from the inner face of the gear 84 is a similar clutch pin 88. Slidable within an axial bore 90 in the shaft 76 is a rod 92 from which extend radially a pair of clutch pins 94 and 96. The roll 70 is secured by a setscrew 98 to the shaft 76. A slot 100 formed in the body portion of the roll 70 registers with a slot 101 formed in the shaft 76, both slots extending in a direction parallel to the axis of the shaft 76 to accommodate movements of the clutch pin 94 when the rod 92 is shifted axially. A similar slot 102 formed in the roll 70 registers with a slot 103 formed in the shaft 76, both slots extending in a direction parallel to the axis of the shaft 76 to accommodate similar movements of the clutch pin 96. The slots 100 and 102 serve the further purpose, in conjunction with the pins 94 and 96, of keying the roll 70 to the shaft 76. The rod 92 is shifted axially by a lever 104 (see also Fig. 2)

fulcrumed upon a pin 106 secured in a bracket 107 carried by one of the stationary spider arms 42. At one end of the lever 104 is a hand grip 108 and at the other end is an antifriction roll 110 which engages between a pair of collars 112 secured on the rod 92. It is evident that the operator, in swinging the lever 104 to his left, will shift the rod 92 to the right and thereby bring the pin 94 into the path of movement of the pin 86, causing the shaft 76 and the roll 70 to be driven counterclockwise as seen in Fig. 1. Swinging of the lever 104 to the operator's right will bring the pin 96 into the path of movement of the pin 88 to reverse the direction of rotation of the roll 70. The lever 104 is normally held by a spring detent 113 in a neutral position wherein neither of the clutch pins 94 and 96 is in clutch-engaging position. With the lever 104 in this neutral position, the roll 70 is therefore stationary. The detent 113 is engageable with an appropriate one of three recesses 115 formed in the bracket 107 to hold the lever in its neutral position or in either one of its operating positions.

Each carriage 30 has a pair of rolls 114 (Figs. 1, 2 and 8) which roll upon the upper surface of the track 32. Each of the rolls 114 has a pair of flanges 116 which engage oppositely disposed finished surfaces on the track 32 to hold the roll 114 against endwise movement. The carriage 30 has also a pair of rolls 118 which engage the under surface of the track 32 and which are provided with flanges 120 engaging oppositely disposed finished surfaces of the track to hold the rolls against endwise movement relative to the track. The carriages 30 are thus mounted for free movement along the track 32.

The jack 28 is fulcrumed upon a pin 122 secured in the carriage 30 and is urged in a counterclockwise direction, as seen in Figs. 1 and 5, by a torsion spring 124 surrounding the pin 122. The jack 28 is normally maintained in an upright stop position by a rod 126 (Figs. 5 and 6) carrying at one end a block 128 in which is formed a vertical slot 130 engaging a pin 132 extending from the jack 28 in a direction parallel to the pin 122. The rod 126 is rigidly secured to a slide 134 which is guided for horizontal movement forwardly and rearwardly in a guideway 136 formed in a block which constitutes a portion of the carriage 30. Formed in the upper portion of the slide 134 is a longitudinal groove 138 into which extends the end of a stop pin 140. The engagement of the end of the pin 140 with the end of the groove 138 limits the rotation of the jack 28 about the pin 122 under the influence of the spring 124 and thus holds the jack 28 normally in its upright position.

Guided for heightwise sliding movement in the jack 28 is a rod 142 (Figs. 1 and 4) which carries a block 144 in its upper end. The block 144 is channel shaped, having a pair of side flanges 146 which engage the opposite side portions of the cone of the last L. Extending up from the block 144 is a last pin 148 which engages the usual thimble hole of the last. The block 144 is pivotally mounted upon a pin 150 secured in the upper end portion of the rod 142 and it may be locked in any one of three angular positions by means of an arm 152 rigidly extending from the block. This arm 152 carries a spring detent which is engageable with any one of three holes 154 formed in an arcuate bracket 156 carried by the rod 142. The height of the last may be adjusted by means of a hand wheel 158 which turns a pinion 160 engaging a rack formed on the rod 142.

The hand wheel 158 is slidably keyed by a pin 300 to a shaft 302 upon which the pinion 160 also is secured. Longitudinal movement of the hand wheel 158 on the shaft 302 is limited by the engagement of the pin 300 with the ends of a slot 304 in the shaft. The shaft 302 is journaled in bearings 306 carried by the jack 28. Slidably mounted in a bore in one of the bearings 306, parallel to the shaft 302, is a locking pin 310 engageable with one of a plurality of holes in the pinion 160. A head 312 on the pin 310 engages a circumferential groove in the hub of the hand wheel 158 to control the position of the locking pin in its bore. A coil compression spring 314 urges the hand wheel, and therefore the locking pin, to the right, into locking position to prevent undesired turning of the hand wheel. When an adjustment is to be made, the operator draws the hand wheel to the left to disengage the locking pin from the pinion; then he turns the hand wheel to the desired position of adjustment; and then he releases the hand wheel, after turning it slightly to enable the locking pin to engage the nearest hole in the pinion.

The arrangement for driving the carriages 30 between stations and for latching them at the stations comprises a plurality of dogs 162 carried by the rotating ring 34 and extending radially outward therefrom. Each carriage 30 carries an abutment 164 (Fig. 6) which constitutes the end portion of a slide 166 movable radially to bring the abutment 164 into or out of the path of the dogs 162. The slide 166 is mounted for such radial movement in a guideway 168 formed in a portion of the carriage 30, the slide being retained in its guideway by a cover plate 167. The slide 166 is urged radially inward toward engaging position by a coil compression spring 170 housed in a groove formed in the upper portion of the slide 166, both ends of the groove being closed. One end of the spring 170 bears against the inner end of the groove and the opposite end of the spring bears against the end of a rack 172 which is slidable in the groove. The spring 170 thus normally holds the rack 172 against the outer (left in the drawing) end of the groove. The teeth of the rack 172 extend upwardly and engage a pinion 174 carried by a shaft 176 (Fig. 1) journaled in the carriage 30. The pinion 174 is engaged also by teeth extending downwardly from a rack 178 which is slidable in a guideway formed in the carriage 30. Secured to the rack 178 is an upstanding pin 180 which carries an antifriction roll 182. This roll, under the influence of a spring 183 acting upon the rack 178, normally bears against an external cylindrical surface 184 of the track 22 and thereby limits the inward radial movement of the rack 178. A recess 186 (Fig. 2) is formed in the bearing surface 184 at station 20 to permit the rack 178 to move radially inward at that station. Such movement of the rack 178 turns the pinion 174 and thereby moves the slide 166 radially outward, disengaging the abutment 164 from the dog 162. The movement of the carriage 30 along the track thereupon stops and the carriage is locked stationary by the engagement of the roll 182 with the recess 186. A similar recess 188 diametrically opposite to the recess 186 is formed in the bearing surface 184 to stop the carriage at station 22.

Secured to and depending from the slide 166 is a pin 190 (Figs. 5 and 6). A slot 192 formed in the cover plate 167 accommodates radial movement of the pin 190. Each of the carriages 30

has extending circumferentially from it a cam 194 (Figs. 2 and 5) the purpose of which is to unlatch the following carriage 30 from the rotating ring 34 when the pin 190 of the following carriage engages and rides up upon an inclined surface 196 of the cam. Such unlatching of the following carriage 30 is permitted by the yielding of its spring 170 as its pin 190 is forced outwardly, or to the left as seen in Figs. 5 and 6. Each carriage is thus automatically unlatched from the rotating ring 34 before striking against a carriage which is already stationary. When the pin 190 of any one of the carriages 30 engages the cam surface 196 of the preceding carriage, the spring 170 will yield to accommodate the unlatching movement of the slide 166.

When any one of the carriages 30 is locked in one of the operating stations 20 or 22, the operator at that station may unlock it and couple it to the driving mechanism by swinging a lever 198 (Figs. 1 and 2) secured to the shaft 176, thereby turning the pinion 174 in a direction to move the roll 182 out of the recess 186 and also to advance the abutment 164 into the path of movement of the next dog 162. As soon as the carriage 30 has been moved by the next dog 162 far enough for the roll 182 to ride again upon the surface 184, the abutment 164 will be maintained in its inward or driving position by the rack 178. The movement of any one carriage away from the operating station at which it has been at rest will release any other carriage which has been stopped by the engagement of its pin 190 with the cam 194 of the carriage which was at rest.

The shoe S is brought into operative engagement with the friction belt 24 while the carriage 30 is at the station 20. The operator accomplishes this by swinging a lever 200 (Figs. 1, 2 and 3) extending from a shaft 202 (Fig. 5) which, in turn, is journaled in the forwardly extending stationary spider arm 42. Secured upon the shaft 202 is a pinion 204 which engages a rack 206 slidable forwardly and rearwardly in a guideway 208 formed in the spider arm. A coil compression spring 210 surrounding a rod 212 is interposed between a stationary abutment 214 and a stop collar 216 secured upon the rod 212. The rod 212 constitutes a rearward extension of the rack 206 and is mounted for sliding movement with the rack. The collar 216 limits the forward (or radially outward) movement of the rack 206 under the influence of the spring 210 by engagement with the rear end of the guideway 208, thus normally maintaining the rack 206 in its forward stop position. Extending forwardly from the rack 206 is a hook 218 which is engageable with a hook 220 extending rearwardly from the rod 212. When the carriage 30 of the jack assembly, which includes the rod 126, moves into stop position at station 20, the hook 220 will move into engagement with the hook 218 and interlock therewith and, when thus interlocked, the hook 220 will be able to transmit rearward movement of the rack 206 to the rod 126. It is evident, therefore, that when the carriage 30 is locked in station 20 the operator, by pulling forward on the lever 200, can swing the jack 28 about its fulcrum 122 and thereby bring the counter portion of the shoe S into engagement with the friction belt 24. Upon release by the operator of the lever 200, the torsion spring 124 and the coil spring 210 will work together to restore the jack 28 to its upright stop position.

For performing relasting operations, the machine is provided with a horn 222 (Figs. 4 and 7)

which is secured to the adjacent ends of a pair of coaxial shafts 224 journaled in bearings 226. The shafts 224 are each normally held in a stop position by torsion springs 228, said position being determined by pins 230 extending radially from the shaft and engaging the ends of circumferential grooves 232 formed in the bearings 226. The bearings 226 are carried upon the forward ends of a pair of parallel slide bars 234 which are urged forwardly to a normal stop position by coil compression springs 236 abutting at their forward ends against collars 238 secured to the slide bars and at their rear ends against the forward ends of guideways 240 in which the bars 234 are slideable. Secured upon the rear ends of the slide bars 234 are collars 242 which engage the rear ends of the guideways 240 to limit forward movement of the slide bars. Each guideway 240 is carried upon an arm 244 which is secured by a set screw 245 upon a shaft 246 extending parallel to the axis of the roll 68 and journaled in a bearing formed in the bracket 74. A hand grip 248 extending upwardly from the arm 244 enables the operator to swing the horn 222 into and out of operating position. The horn 222, when not in use, normally hangs by gravity in the position shown in Fig. 1, with the bearings 226 resting against the base of the bracket 74.

The operation of the machine will now be described. A supply of shoes tightly fitted about the lasts upon which they have been assembled have been placed within reach of the operator at station 20 and the motor 64 has been started to drive the ring 34 and the bevel gears 82 and 84. The operator shifts the handle 108 to his right to engage the roll 70 with the gear 84 thereby causing the friction belt 24 to be driven in a clockwise direction as seen in Fig. 1, and he takes one of the lasted shoes and mounts the last upon the last pin 148. He thereupon grasps the lever 200 and pulls it toward him to bring the counter portion of the shoe forcibly into engagement with the friction belt 24, causing the counter portion of the shoe to be raised relatively to the last. He then releases the lever 200 and draws the lever 198 toward him to unlock the carriage 30 and couple it to the rotating ring 34. The carriage is thus moved toward station 22 and it will come to that station and automatically be locked there if the station is unoccupied. The operator at station 22 will remove the loosened shoe from its last and perform a stitching operation upon it. This operation may be performed, for example, upon a Littleway stitching machine. When the shoe has thus been stitched, the operator at station 22 places it loosely upon the same last from which he had taken it and draws the lever 198 toward him to unlock the carriage 30 and couple it again to the ring 34. The carriage is thus returned to station 20, and assuming that station to be unoccupied, it will automatically be locked there. The operator at station 20 now swings the handle 108 to its extreme left-hand position thereby coupling the roll 70 to the gear 82 and causing the friction belt 24 to be driven in a counterclockwise direction. He then grasps the handle 248 to bring the tip of the shoe horn 222 between the heel portion of the last and the interior of the heel end of the shoe. He then pulls the lever 200 toward him to bring the counter portion of the shoe forcibly into engagement with the friction belt 24 and the action of the friction belt against the counter portion of the shoe urges it downwardly upon the

last, thereby relasting the shoe. The operator thereupon releases the lever 200 and pulls the handle 248 toward him to release the horn 222 from between the last and the shoe. The operation upon that shoe and last is now complete and he removes the last from the last pin and proceeds as before with another lasted shoe.

If either of the operating stations is occupied by one of the carriages 30 while another carriage is being advanced toward it, the second carriage will automatically halt when its pin 190 comes into engagement with the cam 194 of the stationary carriage and it will remain stalled until the carriage preceding it has been moved away from the operating station. The operator at either station is thus afforded a certain amount of leeway in the timing of his operation inasmuch as several carriages may be allowed to stall at his station at the same time.

Having described my invention, what I claim as new and desire to secure by Letters Patent of the United States is:

1. In a machine for use in the manufacture of shoes, the combination of a last support movable through a plurality of operating stations, means for moving the last support through said stations, means at one of said stations for loosening a shoe upon a last on said last support, and means for detaining the last support at a succeeding station to permit the loosened shoe to be removed from the last.

2. In a machine for use in the manufacture of shoes, the combination of a last support movable through a plurality of operating stations, means for moving the last support through said stations, means for detaining the last support at each station, and a relasting device at one station for relasting a shoe which has been loosely placed on a last on the last support at a preceding station.

3. In a machine for use in the manufacture of shoes, the combination of a conveyor having two operating stations, a support for a last on said conveyor, and a combined delasting and relasting device for performing their respective functions upon a shoe on the last at one of said stations, said device serving partially to delast a shoe to facilitate removal of the shoe from the last at the other station and to force the shoe more firmly upon the last after the shoe has been replaced loosely upon the last and returned to the station adjacent to the device.

4. In a machine for use in the manufacture of shoes, the combination of a last support movable through a plurality of operating stations, means for moving the last support through said stations, a driven tool at one of said stations operable when driven in one direction to delast a shoe and when driven in the opposite direction to relast a shoe, and means for reversing the direction of drive of said tool to enable a shoe on a last first to be delasted and then, after being carried loose on the last to another station for further operation and returned loose on the last to the station adjacent to the tool, to be relasted.

5. In a machine for use in the manufacture of shoes, the combination of means for moving a shoe relatively to a last upon which the shoe is mounted, a support for the last, a carriage upon which said last support is mounted for movement to bring the shoe into operative engagement with said shoe-moving means when the carriage occupies a position adjacent to said shoe-moving means, and means for guiding said

carriage for movement between said position and a position remote from said shoe-moving means for convenience in performing another operation.

6. In a machine for use in the manufacture of shoes, the combination of means for loosening a shoe relatively to a last upon which the shoe is mounted, a support for the last, a carriage upon which said last support is mounted for movement to bring the shoe into operative engagement with said loosening means when the carriage occupies a position adjacent to said loosening means, and means for moving the carriage from said position to a position remote from the loosening means for convenience in performing another operation.

7. In a machine for use in the manufacture of shoes, the combination of a relasting device, a support for a last, a carriage upon which said last support is mounted for movement to bring a shoe loose on the last into operative engagement with the relasting device to cause the shoe to be relasted when the carriage occupies a position adjacent to the relasting device, and means for moving the carriage from a convenient operating position remote from said relasting device into said adjacent position.

8. In a machine for use in the manufacture of shoes, the combination of a driven tool operable when driven in one direction to delast a shoe and when driven in the opposite direction to relast a shoe, a support for a last, a carriage upon which said last support is mounted for movement to bring a shoe on the last into operative engagement with said tool to cause the shoe to be delasted when the carriage occupies a position adjacent to said tool, means for moving the carriage first from said adjacent position to a position remote from the tool for convenience in performing another operation upon the delasted shoe and then back to said adjacent position, and means for reversing the drive of said tool to cause the delasted shoe to be relasted when brought again into engagement with the tool.

9. In a machine for use in the manufacture of shoes, the combination of a last support movable through a plurality of operating stations, means for moving the last support through said stations, a tool at one of said stations for effecting relative movement between a shoe on a last on said support and the last, and manually operated means for effecting operative engagement between the shoe and the tool when the last support is at that station.

10. In a machine for use in the manufacture of shoes, the combination of a driven rotary friction tool for moving a shoe relatively to a last on which the shoe is mounted, a support for the last, a carriage on which said last support is mounted for movement to bring the shoe into operative engagement with said tool when the carriage occupies a position adjacent to said tool, manually operated mechanism for thus moving the last support to cause the shoe to engage the tool, and means for guiding the carriage for movement between said position and a position remote from said shoe-moving means for convenience in performing another operation.

11. In a machine for use in the manufacture of shoes, the combination of a driven rotary friction tool for moving a shoe relatively to a last on which the shoe is mounted, a track, a carriage movable along said track between operating stations adjacent to and remote from said tool, a lever pivotally mounted on said carriage and adapted to carry a last with a shoe thereon, and

manually operated mechanism engageable with said lever when the carriage occupies the station adjacent to said tool, said manually operated mechanism being constructed and arranged to move the lever to cause the shoe to be pressed against said tool.

12. In a machine for use in the manufacture of shoes, the combination of a support for a last, a carrier on which said last support is mounted, a tool for operating upon a shoe on the last, means for moving said carrier into and out of an operating station adjacent to said tool, means for disengaging the carrier from the moving means and for holding the carrier in said station, and manually operable means for moving the last support to cause the shoe to engage the tool while the carrier is in said station.

13. In a machine for use in the manufacture of shoes, the combination of a jack for supporting a last, a carrier upon which said jack is pivotally mounted, a tool for operating upon a shoe on the last, means for moving said carrier into and out of an operating station adjacent to said tool, means for disengaging the carrier from the moving means and for holding the carrier in said station, and manually operable means for swinging the pivotally mounted jack to bring the shoe on the last into operative engagement with the tool while the carrier is in said station.

14. In a machine for use in the manufacture of shoes, the combination of a jack for supporting a last, a carrier upon which the jack is movably mounted, a tool for operating upon a shoe on the last, means for moving the carrier into and out of an operating station adjacent to said tool and for holding the carrier in said operating station, mechanism supported independently of the carrier for moving the jack relatively to the carrier to bring the shoe on the last into operative engagement with the tool, and a normally disengaged connection between said mechanism and the jack, said connection being on the carrier and being constructed and arranged to come into operative connection with said jack-moving mechanism when the carrier moves into said operating station.

15. In a machine for use in the manufacture of shoes, the combination of a plurality of jacks for supporting lasts, a carrier for each of said jacks, the jacks being mounted for movement relatively to their carriers, a tool for operating upon shoes on the lasts, means for moving the carriers into and out of an operating station adjacent to said tool and for holding the carriers in said operating station, a device for moving the jacks relatively to their carriers to bring the shoes on the lasts into operative engagement with the tool, and a normally disengaged connection on each of the carriers, each of said connections being constructed and arranged to come into operative engagement with said jack-moving device to connect the associated jack with the device when the associated carrier moves into the operating station.

16. In a machine for use in the manufacture of shoes, the combination of a circular stationary substantially horizontal track, a work support movable on said track between operating stations, a frame for supporting said track, a driving ring coaxial with said track, means for coupling said work support to said driving ring, a drive shaft coaxial with said track, a tool supported by said frame for operating on a shoe on said work support, a driving connection from said shaft to said tool, and a driving connection from said shaft to

said ring, said ring being rotatably mounted on said frame at a locality below the level of that portion of the shaft to which the tool driving connection is connected.

17. In a machine for moving shoes relatively to lasts, a rotary friction tool, a support for a last with a shoe thereon, means for moving said support to bring the counter portion of the shoe into engagement with the tool, driving means for said tool, and a reversing gear in said driving means for enabling the tool to be driven in one direction to delast a shoe on the last and in the oppo-

site direction to relast a shoe loosely mounted on the last.

JOHN T. LANCASTER.
